(57) CLAIM

The ornamental design for a headdress, as shown and described.

DESCRIPTION

FIG. 1 is a front perspective view of a headdress; FIG. 2 is a front view of the headdress of FIG. 1; FIG. 3 is an enlarged detail front perspective view of the portion of the headdress within the area identified as "3" in FIG. 1; FIG. 4 is an enlarged detail side perspective view of the portion of the headdress within the area identified as "3" in FIG. 1; FIG. 5 is an enlarged detail front view of the portion of the headdress within the area identified as "5" in FIG. 2; and, FIG. 6 is an enlarged detail back view of the portion of the headdress within the area identified as "5" in FIG. 2. The dashed broken lines in the figures are included for the purpose of illustrating unclaimed portions of the headdress that form no part of the claimed design. The dot-dash broken lines in the figures are used to identify the areas of enlargement with the dot-dash broken lines forming no part of the claimed design.

1 Claim, 5 Drawing Sheets
